(57) **CLAIM**

The ornamental design for the ball for athletic sports, as shown and described.

DESCRIPTION

FIG. 1 is a perspective view of the ball for athletic sports according to my design;

FIG. 2 is a front view thereof, the rear view being identical to the front view when rotated clockwise 60°;

FIG. 3 is a right side view thereof, the left side view being a mirror image of the right side view; and,

FIG. 4 is a top plan view thereof, the bottom plan view being identical to the top plan view.
